UNITED STATES PATENT OFFICE

164,543

MEAT TENDERIZING MACHINE

Sidney Bakewell, Detroit, Mich.

Application August 16, 1950, Serial No. 11,783

Term of patent 7 years

(Cl. D55—1)

To all whom it may concern:

Be it known that I, Sidney Bakewell, a citizen of the United States, residing at Detroit, in the county of Wayne and State of Michigan, have invented a new, original, and ornamental Design for Meat Tenderizing Machine, of which the following is a specification, reference being had to the accompanying drawing forming part thereof in which—

Fig. 1 is a perspective view showing the front and one end of a meat tenderizing machine embodying my new design.

Fig. 2 is a perspective view showing the front and opposite end thereof.

Fig. 3 is an elevation taken from the right hand end of Fig. 1.

The lower upright rear wall is plain and flat

and terminates at its upper portion in the forwardly and upwardly inclined flat and plain surface.

What I claim is:

The ornamental design for a meat tenderizing machine, substantially as shown and described.

SIDNEY BAKEWELL.
